ELECTRICALLY OPERATED HOT AIR FURNACE

Agnes Gertrude Watson and Albert Edward Robingson, London, Ontario, Canada

Application May 17, 1932. Serial No. 611,886

1 Claim. (Cl. 219—38)

Our invention relates to improvements in electrically operated hot air furnaces and the object of the invention is to provide an improved means for operating a hot air furnace through the medium of electrical heating elements.

5 A further object is to provide means to cause the air to be heated to pass up between and through the heating elements which are of perforated construction, the faces of said elements being positioned in inclined diverging planes.

10 A still further object is to provide means for supporting the elements in the above position in the furnace casing.

With the above and other objects which will 15 hereinafter appear our invention consists in its preferred embodiment of a construction all as hereinafter described and illustrated in the accompanying drawing in which,

20 Fig. 1 represents a vertical section through a hot air furnace casing of our particular construction showing the heating elements positioned therein.

Fig. 2 is a horizontal section through the line 2—2 Figure 1.

25 Fig. 3 is a perspective detail of the tripod stand for supporting each element and,

Fig. 4 is a cross sectional view through one of the elements.

30 Like characters of reference indicate corresponding parts in the different views.

35 A hot air furnace control constructed to adapt itself for use with our heating elements may well comprise a cylindrical casing 1 provided with a suitable heat insulating lining 2 and the usual truncated, conical top portion 3. A cold air inlet 4 is provided in the lower portion of the casing 1 for the admission of the cold air to the furnace and such inlet of cold air may be produced by means of a forced draft such as by employing a 40 circulating fan. This circulating system however forms no part of our invention and is therefore not described.

45 In the upper part 3 of the furnace casing we provide the hot air outlet 5 which is adapted to be connected with the usual hot air pipes to the house registers. Obviously the outlet 5 may be duplicated around the upper portion 3 of the casing 1 as described, depending upon the number of pipes to be connected to this upper portion 50 which constitutes a header therefor.

Our heating elements 6 are preferably of the disk type having perforations 7 therethrough the heating element resistance wires 8 being spirally wound therein and enclosed.

55 Any suitable form of heating elements can be used and such elements are adapted to be supported with their faces in planes diverging outwardly away from the vertical from bottom to top.

The disk elements 6 preferably consist of a 60 composition which is an admixture of high tem-

perature cement, fireclay, pumice and keen cement in which the wires 8 are embedded as above described.

In order to support the elements 6 in the above referred to position we provide tripod stands 9 having preferably a single inner leg 10 and two outer legs 11. The inner leg 10 supports the bottom of heating elements 6 and the outer legs 11 are adapted to be secured to or rest against the back of the heating element. In this way 70 the elements are supported facing each other in inclined positions.

The cold air as above described is admitted through the inlet 4 and when the heating elements are functioning such air passes upwardly 75 in the furnace casing 1 between the elements 6 as well as through the perforations therein being heated in the process and the hot air being discharged through the outlet 5 into the circulating pipe or pipes (not shown). The insulation 80 2 prevents the heated air in the casing from warming the surrounding air ensuring that it be passed in a heated condition to the outlet 5.

The control of the functioning of the electric heating elements can be achieved by a thermostat if so desired but as this forms no part of the present invention it is not described.

From the above description it will be seen that we have devised a simple and effective means of heating the air in hot air furnaces through the medium of electric heating elements wherein the consumption of the current will not be excessive due to the particular position of the heating elements. It is to be understood that such heating elements are preferably of the heat absorbing 90 type, the disks being composed of heat absorbing cementitious material or the like.

What we claim as our invention is:

In an electrically heated hot air furnace, the combination with a furnace casing having a cold air inlet and a hot air outlet in the vicinity of the bottom and top thereof respectively, of a plurality of spaced apart electrical heating elements arranged in the casing between the cold air inlet and the hot air outlet, each element being 100 inclined outwardly away from the vertical from bottom to top and a tripod stand for supporting each element in the inclined position in the casing between the cold air inlet and the hot air outlet, said stand comprising an inner leg for 105 supporting the lower edge of an element and a plurality of legs for supporting the upper part of an element.
